UNITED STATES PATENT OFFICE.

ALBEN E. LUNDELL, OF NEW YORK, N. Y., ASSIGNOR TO WESTERN ELECTRIC COMPANY, INCORPORATED, A CORPORATION OF NEW YORK.

MACHINE-SWITCHING TELEPHONE SYSTEM.

Application filed December 18, 1920. Serial No. 431,558.

To all whom it may concern:

Be it known that I, ALBEN E. LUNDELL, a citizen of the United States, residing at New York, in the county of Bronx, State 5 of New York, have invented certain new and useful Improvements in Machine-Switching Telephone Systems, of which the following is a full, clear, concise, and exact description.

10 This invention relates to telephone exchange systems, and more particularly to machine switching telephone systems in which provision is made for supplying subscribers with measured service.

15 The three main classes of service usually supplied to subscribers, are either measured service, in which case, a message register is used to count the number of calls, coin box service, in which the subscriber pays for 20 each call as it is made, and flat rate service, in which the subscriber merely pays a fixed amount of money for the use of his telephone over a fixed period of time. Methods for operating message registers and coin collect 25 devices are well-known in the art. Since, however, different methods are employed to collect a coin from those required to operate a message register, it has been the previous practice to segregate the subscribers in accordance with the class of service to which 30 they are entitled so that upon completion of a successful call, their charging devices may be operated by the proper character of current. This arrangement is satisfactory so 35 long as the subscribers may be divided into equal groups, but it frequently happens that there will remain a fraction of a group of subscribers entitled to each kind of service. To give each of these small groups of sub- 40 scribers access to a particular type of switch arranged for meeting the requirements of their particular type of toll device, results in an inefficient use of the apparatus.

45 It is the object of this invention to provide a switching arrangement such that a number of lines, which differ with respect to the class of service to which they are entitled, may all have access to the same type of first selector, and in case of successful calls, the charge will be properly made.

A feature of the invention is the setting up

of a discriminating condition in the first selector switch circuit, which will, at the proper time, determine the type of charging 55 apparatus to be put into use.

A further feature of the invention resides in the use of various resistances bridged across the line conductors to control a relay combination at the selector switch for the 60 purpose above set forth.

It is thought that the invention will be best understood from the following detailed description, reference being had to the accompanying drawings.

In the drawings, Fig. 1, shows diagrammatically, the substation circuits of three subscribers' lines; the first being a flat rate line, the second a coin box line, and the third, a message register line. The circuits 70 of a line finder and auxiliary apparatus are also shown in this figure. Fig. 2 shows such portions of a first selector switch and the sending and registering devices as are necessary to a complete understanding of 75 the invention.

The invention has been shown applied to a full automatic system employing switches of the type set forth in Patent No. 1,123, 696, issued January 5, 1915, to E. B. Craft 80 and J. N. Reynolds. It is to be understood, however, that the system shown is for the purpose of illustration only, and the invention is, therefore, not to be restricted thereto. A description of the operation of the 85 system, when a flat rate subscriber initiates a call, will first be given.

When the subscriber at substation 1 removes his receiver from the hook, a circuit is completed from grounded battery, winding of line relay 2, left-hand armature and back contact of cut-off relay 3, conductor 4, the substation apparatus of the calling subscriber, conductor 5, and the right-hand armature and back contact of relay 3 to 90 ground. Relay 2 is energized in this circuit and completes a circuit from grounded battery, winding of relay 6, side switch arm 95 7 and its first contact, conductor 8, and the armature and front contact of relay 2 to 100 ground. Relay 6 is energized in this circuit and completes a circuit from grounded battery, winding of side switch magnet 9, and the armature and front contact of relay 6

to ground. Magnet 9 is energized in this circuit, and causes the advance of the side switch out of position 1 and into position 2.

With the side switch in position 2, relay 6 is maintained energized over a circuit extending from grounded battery, winding of relay 6, side switch arm 10 and its second contact, test brush 11 and its first contact to ground. It is to be noted that the first and 10 second contacts served by brush 11 are permanently connected to ground. With the side switch in its second position and with relay 6 energized a self-interrupting circuit for line finder stepping magnate 12 is completed extending from grounded battery, winding of magnet 12, armature and back contact of magnet 12, side switch arm 13 and its second contact, armature and front contact of relay 6 to ground. Magnet 12 is energized and interrupts its own circuit, and upon deenergization causes the line finder 15 brushes 14, 15, 16, 11 and 17 to be moved into engagement with their second contacts. The line finder switch is a single motion rotary 20 switch which may be of any well-known form. In the present embodiment of the 25 invention it has been assumed that this line finder switch is of the type shown and described in an application, Serial No. 317,126, filed August 13, 1919, by O. F. Forsberg and R. M. de Vignier.

When test brush 11 engages its second contact, relay 6 is maintained energized over a circuit identical with that previously described. As a result of the continuous energization of relay 6 magnet 12 is again energized and interrupts its own circuit to advance the line finder brushes into engagement with the third set of contacts. The 30 hunting operation of the line finder switch begins at this point and will continue, due to the fact that magnet 12 will continue to interrupt its own circuit and advance the line finder switch as long as relay 6 35 remains energized. Relay 6 remains energized as long as test brush 11 is passing over the terminals of non-calling lines. The terminals of non-calling lines, whether busy as calling or called subscribers, or of idle lines, 40 will be characterized by the presence of ground potential on their respective test terminals in the line finder bank, due to the fact that the line relays of such lines will be deenergized and supply ground potential 45 by way of their right-hand armatures and back contacts to such test terminals, as is obvious from inspection of the drawings.

When the line finder brush set engages the terminal set of the calling subscriber's line, 50 relay 6 will be deenergized, since no ground potential will be found by brush 11, due to the fact that line relay 2 is energized. Relay 6 will therefore become deenergized and prevent further operation of magnet 12,

thus causing the brush set to remain in engagement with the terminals of the calling subscriber's line. The deenergization of relay 6 also opens the original energizing circuit for side switch magnet 9 and this relay deenergizes and causes the side switch to be moved into its third position.

In position 3 of the side switch, marginal relays 18 and 19 have an opportunity to function in order to register the class of service, with regard to call charging, which shall be provided by the selector circuit.

Since the calling subscriber's line is a direct or flat rate line, that is, provided with neither a message register nor a coin box, ground potential will be supplied at this time to the tip conductor of the line by way of the right-hand armature and back contact of cut-off relay 3. Battery potential is supplied to the ring conductor of the line by way of the low resistance winding of line relay 2. Relay 19 is energized due to the closure of a circuit extending from grounded battery, right-hand winding of relay 19, side switch arm 20 and its third contact, brush 14, tip conductor 24 to ground, at the right-hand armature and back contact of relay 3. Relay 19 is energized and locks up through its left-hand winding and left-hand armature and front contact to conductor 25, which is grounded at the lower left-hand contact of sequence switch spring 26.

A circuit is completed at the same time for relay 18. This circuit extends from grounded battery, left-hand winding of relay 18, side switch arm 21 and its third contact, brush 15, ring conductor 27, through the sub-station apparatus, and to ground at the right-hand armature and back contact of cut-off relay 3. The winding of relay 18 is, however, shunted by the low resistance winding of relay 2, to prevent the energization of relay 18.

It is to be noted that with the side switch in position 3 a circuit is completed from grounded battery, winding of slow pull up relay 28, side switch arm 23 and its third contact to ground. Relay 28 becomes energized and starts to attract its armature, but since it is slow to pull up relays 18 and 19 have an opportunity to pull up and lock to conductor 25 before relay 28 completes the attraction of its armature. When the armature of relay 28 is completely attracted a circuit is completed from grounded battery, winding of side switch magnet 9, side switch arm 13 and its third contact, armature and front contact of relay 28 to ground. Magnet 9 is energized and causes the advance of the side switch out of position 3 and into position 4. In position 4 of the side switch, side switch magnet 9 is maintained energized by a circuit extending from grounded battery, winding of magnet 9, side switch arm

13 and its fourth contact, conductor 29, upper left-hand contact of sequence switch spring 26 to ground.

In position 4 of the side switch, cut-off relay 3 is energized by a circuit extending from ground, winding of relay 3, conductor 30, brush 16 and its associated terminal, side switch arm 22 and its fourth contact, resistance 31 to grounded battery. The resultant energization of relay 3 causes the de-energization of line relay 2 in the well-known manner.

In position 4 of the side switch the step-by-step registers of the sender, shown in Fig. 2, are placed under the control of the subscriber's dial, who may now send impulses to control the setting of such registers.

It is to be understood that the invention is capable of adaptation to the system of any desired capacity. For the sake of simplifying description it has been assumed that the line finder switch is directly connected to a final switch and that there are only one-hundred subscribers in the system. The mechanical structure of the switch, whose controlling circuits are shown in Fig. 2 is a simplification of the switch shown in Patent No. 1,123,696, issued January 5, 1915 to E. B. Craft and J. N. Reynolds, and is of the well-known power driven panel type selector.

In the present case it has been assumed that one brush only is provided and that this brush has access to ten groups of ten lines each. The step-by-step registers, as part of the sender, are of a mechanical structure substantially similar to that shown in the application mentioned above in connection with the line finder switch. It is to be understood that in a practical system the sender would be associated with the selector switch by means of a sender selector or a cord finder and that a number of these senders would be common to the various selector and finder units. For the sake of simplicity it has been assumed that there is a sender permanently associated with each connecting link.

With the side switch in position 4 a circuit is completed from grounded battery, winding of stepping relay 32, conductor 33, side switch arm 21 and its fourth contact, brush 15 and its associated contact, conductor 27, through the substation apparatus of the calling subscriber including a sending device 34, conductor 24, brush 14 and its associated contact, side switch arm 20 to ground. Relay 32 is energized in this circuit and completes a circuit from grounded battery, winding of slow release relay 35, armature and front contact of relay 32 to ground.

Assuming that the number of the wanted subscriber is 23 the calling subscriber will now operate his impulse sending device 34 to

send the first series of impulses comprising a train of two impulses. As a result relay 32 will be deenergized two times. Upon the first deenergization of relay 32 a circuit is completed from grounded battery, winding of stepping magnet 36 of the tens register, conductor 37, side switch arm 38, winding of slow release relay 39, armature and front contact of relay 35, which, being slow to release, remains energized during the sending of the impulses, armature and back contact of relay 32 to ground. Magnet 36 is energized and as soon as relay 32 again energizes the stepping magnet deenergizes to cause the advance of tens register brushes 40 and 41 into engagement with the first off-normal terminals in their respective banks. Slow release relay 39 is energized in series with stepping magnet 36 and remains energized until the completion of the sending of the first set of impulses. The tens register makes a step upon each de-energization of relay 32 and is therefore in its second off normal position when the sending of the first series of impulses is completed.

After the first series of impulses has been sent, stepping relay 32 will remain energized over a relatively long period of time, thus causing the deenergization of relay 39. It is to be noted that while relay 39 was energized side switch stepping magnet 42 was energized by a circuit extending from grounded battery, winding of magnet 42, armature and front contact of relay 39 to ground. The side switch comprises arms 43, 38 and 44, and is a simple rotary switch controlled by magnet 42, which in each position causes the switch to be advanced upon de-energization. The deenergization of relay 39 therefore causes the deenergization of magnet 42 and the resultant advance of the side switch controlled by it into position 2.

With the sender side switch in position 2, a circuit is completed from ground, power magnet of sequence switch 45, upper left-hand contact of sequence switch spring 46, side switch arm 43 and its second contact to ground, for moving this sequence switch out of position 1 and into position 2.

The calling subscriber now operates his dial to send three impulses to record the units designation on the units register, which comprises brushes 47 and 48 with their associated contact banks and a controlling stepping magnet 49. The first interruption of the line circuit causes relay 32 to be deenergized and completes a circuit from grounded battery, winding of magnet 49, conductor 50, side switch arm 38 and its second contact, winding of slow release relay 39, armature and front contact of slow release relay 35, armature and back contact of relay 32 to ground. Relay 39 is

energized and causes in turn the energization of side switch stepping magnet 42. Magnet 49 is energized and when relay 32 again deenergizes causes the register brushes 47 and 48 to engage their first off-normal contacts. The above described operation continues until all the impulses have been sent, at which time brushes 47 and 48 will be in engagement with their third off-normal contacts. The continued energization of relay 32 causes the release of relay 39, which, upon deenergization, causes the release of stepping magnet 42, which advances the side switch arms controlled by it into engagement with their third contacts.

As soon as sequence switch 45 reaches its second position the fundamental circuit is closed to start the selective operation of the switch shown in Fig. 2. This circuit is completed from the grounded battery, winding of relay 51, lower left-hand contact of sequence switch spring 52, conductor 53, winding of stepping magnet 54, contact of sequence switch spring 55, outer armature and back contact of the 0' counting relay, conductor 56, lower left-hand contact of sequence switch spring 57 to ground. Relay 51 is energized in this circuit and locks up to conductor 53 by way of its right-hand armature and front contact and the upper left-hand contact of sequence switch spring 52. The energization of relay 51 also completes a circuit from grounded battery, winding of the power magnet of sequence switch 58, lower right-hand contact of sequence switch spring 59, left-hand armature and front contact of relay 51 to ground, for moving this sequence switch out of position 1 and into position 2.

It is to be observed that stepping relay 54 was energized in series with line relay 51, thus completing a circuit from grounded battery, winding of the No. 1 counting relay, armature and back contact of the No. 1' counting relay, conductor 60, register brush 41 and its second contact, left-hand contact of sequence switch spring 61, armature and front contact of relay 54 to ground. The No. 1 counting relay is energized in this circuit and prepares in the well-known manner a circuit for the No. 1' counting relay.

With sequence switch 58 in position 2 and with relay 51 energized a circuit is completed from grounded battery, winding of up drive power magnet 62, contact of sequence switch spring 63, left-hand armature and front contact of relay 51 to ground. The energization of magnet 62 causes the brush shaft which carries brushes 64, 65 and 66 to be moved upwardly in a group selecting movement. As soon as commutator brush 67 engages the first conducting segment of commutator 68, stepping relay 54 is shunted down, since ground is now

supplied directly to relay 51 by way of the upper right-hand contact of sequence switch spring 52, conductor 69, commutator 68, commutator brush 67 to ground. When the stepping relay 54 deenergizes the shunt is removed from about the winding of the No. 1' counting relay and this relay is energized. As soon as commutator brush 67 engages an insulating segment of commutator 68, relay 54 is again energized and causes the energization of the 0 counting relay. When brush 67 engages the next conducting segment of commutator 68, relay 54 is again short circuited and allows the 0' counting relay to be energized. The energization of the 0' counting relay causes a circuit to be completed from grounded battery, power magnet of sequence switch 45, lower right-hand contact of sequence switch spring 46, conductor 70, inner armature and front contact of the 0' counting relay to ground for moving this sequence switch out of position 2 and into position 3, thus opening the lower branch of the fundamental circuit. When commutator brush 67 engages the next insulating segment of commutator 68, at which time brushes 64, 65 and 66 will be in operative relation to the group of lines numbered 21 to 30, the locking circuit of relay 51 is opened and this relay deenergizes, opening the circuit of up drive magnet 62 and bringing the selector shaft to rest. The deenergization of relay 51 also completes a circuit from grounded battery, power magnet of sequence switch 58, lower left-hand contact of sequence switch spring 59, left-hand armature and back contact of relay 51 to ground for moving this sequence switch out of position 2 and into position 3.

When sequence switch 45 reaches position 3, it is immediately moved into position 4 by a circuit extending from grounded battery, power magnet of sequence switch 45, upper right-hand contact of sequence switch spring 46, side switch arm 43 and its third contact, to ground, provided that the units register has been positioned. If the units impulses have not yet been set, the side switch will be in position 2. Therefore, the sequence switch 45 will wait until the units register has been positioned as evidenced by the advance of the side switch into position 3.

As soon as sequence switch 45 reaches position 4, relay 51 is again energized by means of a circuit extending from grounded battery, winding of relay 51, lower left-hand contact of sequence switch spring 52, conductor 53, winding of stepping relay 54, contact of sequence switch spring 55, outer armature and back contact of the 0' counting relay, conductor 56, lower left-hand contact of sequence switch spring 57 to ground.

The energization of relay 51 completes a circuit from grounded battery power magnet of sequence switch 58, lower right-hand contact of sequence switch spring 59, left-hand armature and front contact of relay 51 to ground, for moving sequence switch 58 out of position 3 and into position 4. In position 4 of sequence switch 58, relay 51 is maintained energized by means of a locking circuit extending through its right-hand armature and front contact. At its left-hand armature and front contact relay 51 supplies ground to up-drive power magnet 62 to cause the brush shaft to be moved upward.

Stepping relay 54 is energized upon the completion of the fundamental circuit, and completes a circuit from grounded battery, winding of the No. 2 counting relay, armature and back contact of the No. 2' counting relay, conductor 71, register brush 47, and its third off-normal contact, contact of sequence switch spring 61, armature and front contact of relay 54 to ground. The No. 2 counting relay is energized in this circuit in the well-known manner and prepares a circuit for the No. 2' counting relay, which is not energized at this time, due to the shunt circuit to ground completed at the armature of relay 54.

As the selector brush shaft is moved upward, commutator brush 72 is advanced into engagement with a conducting segment of commutator 73. As soon as this occurs, relay 54 is shunted out and relay 51 is maintained energized by a path extending to ground by way of the lower right-hand contact of the sequence switch 52, conductor 74, commutator 73, commutator brush 72 to ground. The deenergization of relay 54 allows the No. 2' counting relay to energize. As soon as commutator brush 72 engages an insulating segment of commutator 73, relay 54 is again energized and allows the No. 1 counting relay to be energized. As the shaft moves upward relay 54 is intermittently operated to cause the operation of the counting relays. When the 0' counting relay is energized, a circuit is completed from grounded battery, power magnet of sequence switch 45, lower right-hand contact of sequence switch spring 46, conductor 70, inner armature and front contact of the 0' counting relay to ground, for moving this sequence switch out of position 4 and into position 6. The advance of the selector brush shaft continues until commutator brush 72 engages an insulating segment of commutator 73, at which time the brush set comprising brushes 64, 65 and 66 will be accurately centered at the terminals of the wanted line. Relay 51 thereupon deenergizes and opens the circuit of up-drive magnet 62 and at its left armature and back contact completes a circuit

from grounded battery, power magnet of 65 sequence switch 58, lower left hand contact of sequence switch spring 59, armature and back contact of relay 51 to ground for moving this sequence switch out of position 4 and into position 12.

It is to be understood that in practice sequence switch 58 would be brought to rest in various positions between 4 and 12, in order to accomplish a test to determine whether the called line is busy, and to supply ringing current to the line of the called subscriber if idle. Since these operations are well-known in the art and are not essential to the invention, they have been omitted from the present description, and it will be assumed that the called line was properly signaled, and that the response of the called subscriber caused the advance of sequence switch 58 into position 12.

As soon as sequence switch 45 leaves position 4, the energizing circuit of escape magnet 9, which controls the line finder side switch is interrupted at the upper left-hand contact of sequence switch 26, and this magnet deenergizes and advances the line finder side switch into position 5.

In position 5 of the line finder side switch and position 12 of the selector switch 58, the talking connection is complete, being extended over an obviously traceable circuit through side switch arms 20 and 21 and their fifth contacts, and sequence switch springs 75 and 76 to the left-hand windings of a repeating coil 77 which supplies battery to the substation of the calling subscriber. Calling supervisory relay 78 is energized for a purpose which will appear later. Talking battery is supplied to the called subscriber through the right-hand windings of repeating coil 77, by way of sequence switch contacts 79 and 80, and brushes 64 and 65 and their associated contacts. Current flow in the loop of the called subscriber's line causes the energization of the supervisory relay 81 for a purpose to be set forth hereinafter.

It is to be observed that when sequence switch 58 reaches position 11 the called subscriber's cut-off relay 82 is energized to remove the control of the subscriber's line relay, by means of a circuit extending from grounded battery, winding of relay 82, terminal 83, brush 66, contact of sequence switch spring 84 to ground.

It will be recalled that after the selective operations are completed, sender sequence switch 45 is advanced into position 6. The next stopping position of sequence switch 45 is determined by the condition of relays 18 and 19. In the present case, since the calling line is a direct line, and therefore relay 19 only is energized, sequence switch 45 is moved out of position 6 and into position 8 by means of a circuit extending from

grounded battery, power magnet of sequence switch 45, conductor 95, left-hand contact of sequence switch spring 88, conductor 96, right-hand armature and front 5 contact of relay 19, left-hand armature and back contact of relay 18 to ground.

When conversation is completed the calling and called subscribers will replace their receivers and thus bring about the deenergization of relays 78 and 81. The deenergization of relay 78 completes a circuit from grounded armature and back contact of relay 78, upper contact of sequence switch spring 85, conductor 98, winding of power 10 magnet of sequence switch 58 to grounded battery thus causing the advance of sequence switch 58 out of position 12 and into position 16. In passing through positions 14 and 15 charging current would have been 15 supplied in case the calling line had been either a coin box line or a message register line. Since the line is a direct line no charging current of any kind is supplied.

When sequence switch 58 reaches position 25 16 a circuit is completed from grounded battery, power magnet of sequence switch 45, lower contact of sequence switch spring 91, conductor 99, upper left-hand contact of sequence switch 57 to ground, for moving this sequence switch out of position 8 and into position 16. As soon as sequence switch 45 reaches position 11 a circuit is completed from grounded battery, power magnet of sequence switch 58, conductors 98 and 100, 30 upper contact of sequence switch spring 91, conductor 99, upper contact of sequence switch spring 57 to ground, for moving this sequence switch out of position 16 and into position 17. Sequence switch 58 remains in 35 position 17 until the line finder has been restored to its normal position.

Referring now to the sender circuits, release of the registers take place as soon as sequence switch 45 reaches position 16. The 45 units register is the first to release and is advanced into its normal position by means of a circuit extending from grounded battery, winding of stepping magnet 49, armature and back contact of magnet 49, register 50 arm 48, and an off-normal terminal, contact of sequence switch spring 101 to ground. Magnet 49 interrupts its own circuit until the register brushes 47 and 48 reach their 55 normal positions. As soon as brush 48 reaches its normal position, a self-interrupting circuit is completed for the tens register magnet. This circuit extends from grounded battery, winding of magnet 36, armature and back contact of magnet 36, register arm 60 40 and off-normal contact, the units register arm 48 and the normal terminal, contact of sequence switch spring 101 to ground. Stepping magnet 36 advances the tens register into its normal position, in which position 65 the above traced circuit is opened. As soon

as the registers have been returned to their normal positions, the sender side switch is returned to its normal position since a self-interrupting circuit is completed for side switch stepping magnet 42. This circuit extends from grounded battery, winding of magnet 42, armature and back contact of magnet 42, side switch arm 44 and its third contact, tens register brush 40 and its normal contact, units register brush 48 and its 70 normal contact, contact of sequence switch spring 101 to ground. Magnet 42 advances the side switch one step into its normal position, whereupon a circuit is completed from grounded battery, power magnet of sequence switch 45, upper contact of sequence switch spring 102, side switch arm 44 and its 75 normal contact, register brushes 40 and 48 and their respective normal contacts, contact of sequence switch spring 101 to ground, for moving this sequence switch out of position 16 and into position 1. All parts of the sender apparatus have now been restored to their normal condition.

In position 17 of sequence switch 58, the 80 line finder switch shown in Figure 1, is restored to its normal position due to the completion of a self-interrupting circuit for line finder stepping magnet 12. This circuit extends from grounded battery, winding of magnet 12, armature and back contact of magnet 12, conductor 104, contact of sequence switch spring 87, conductor 105, off-normal segment 103, brush 17 to ground. Magnet 12 advances the line finder switch 85 until brush 17 leaves off-normal segment 103, at which time the line finder will have been advanced into its normal position. The return of the line finder switch causes the 90 restoration of the line finder side switch in 100 a well-known desired manner.

When the line finder switch reaches its normal position, a circuit is completed from grounded battery, power magnet of sequence switch 58, conductor 98, lower left contact 110 of sequence switch spring 85, conductor 106, normal finder contact 104, brush 17 to ground, for moving sequence switch 58 out of position 17 and into position 18.

In position 18 of sequence switch 58 the 115 selector switch is restored. This is accomplished by down drive magnet 94, due to the completion of a circuit extending from grounded battery, winding of magnet 94, upper left-hand contact of sequence switch spring 57 to ground. As soon as commutator brush 67 engages normal commutator segment 107, a circuit is completed from grounded battery, power magnet of sequence switch 58, upper right-hand contact of sequence switch spring 59, segment 107, brush 67 to ground, for moving this sequence switch out of position 18 and into position 120 1. As soon as sequence switch 58 leaves position 18, the circuit of down drive magnet 125 130

94 is opened and the selector brush shaft is brought to rest. All parts of the apparatus have now been restored to their normal positions and are ready for reuse.

- 5 The operation of the system in case a call is originated by a subscriber equipped with but a coin collect device will now be described. A subscriber's substation apparatus of this character is indicated at 107.
- 10 In this case the operation of the system is identical with that previously described up to the point immediately following the seizure of the calling line by the line finder switch. As before, relays 18 and 19 are given an opportunity to energize in position 3 of the line finder side switch, while awaiting the energization of slow pull-up relay 28. In the present case, relay 19 is energized by a circuit extending from grounded battery, right-hand winding of relay 19, side switch arm 20 and its third contact, brush 14, conductor 115 thence through the loop of the calling substation, outer armature and back contact of relay 108 to ground.
- 25 Relay 18 is also energized by a circuit extending from grounded battery, left-hand winding of relay 18, side switch arm 21 and its third contact, brush 15 and its associated contact, conductor 116, outer armature and back contact of relay 108 to ground.
- 30 It is to be observed that relay 19 is shunted by the winding of relay 109, but since relay 109 is a high resistive relay, relay 19 is allowed to be operated. Relays 18 and 19 upon energization lock up to conductor 25 as previously described.

From this point the operation of the system is the same as previously described until after the selector switch has been positioned and the sender sequence switch has been advanced out of position 4 and into position 6. Sequence switch 45 is then advanced out of position 6 through position 8 and into position 10 by means of a circuit extending from grounded battery, power magnet by sequence switch 45, conductor 95, upper right-hand contact of sequence switch spring 88, conductor 97, armature and front contact of relay 18 to ground. In position 10 of sequence switch 45 proper conditions are set up so that in case of a successful call coin collect current will be supplied to coin collect magnet 119.

Assuming that a call has been successful and that the called subscriber has answered, his response will cause the energization of relay 81. A circuit is then completed from grounded battery, winding of relay 92, contact of sequence switch spring 90, armature and front contact of relay 81 to ground. Relay 92 upon energization locks up through its right-hand armature and front contact. When connection is no longer desired release takes place as previously described.

65 When sequence switch 58 reaches position

14, and while passing through this position and through position 15, coin collect current is supplied by way of the left-hand armature and front contact of relay 92 to the lower contact of sequence switch spring 75 over the tip conductor of the link circuit, side switch arm 20 and its fifth contact, brush 14 and its associated terminal, conductor 115, winding of coin collect magnet 119 to ground. The resulting energization of magnet 119 collects the calling subscriber's coin. In case the call had been unsuccessful, supervisory relay 81 would not have been energized and therefore, relay 92 could not have been energized. As a result when the calling subscriber replaced his receiver, release would have taken place as previously described. In this case, however, ground return current would have been supplied to the tip conductor of the line by way of the left-hand armature and back contact of relay 92. The restoration of this system after reaching position 16, takes place in a manner identical with that previously described.

The operation of the system in case a call is originated by a subscriber whose line is equipped with a message register will now be described. A substation of this character is indicated at 110, and is shown with an associated line relay 112, cut-off relay 111, and message register device 113. In this case, the right-hand winding of line relay 112 is of low resistance, corresponding to that of the winding of line relay 2 of a direct line, while the left-hand winding of relay 112 is of a relatively high resistance. In this case the operation of this system takes place as previously described until that stage is reached at which circuits are completed for relays 18 and 19. In the present case neither of these relays will be energized. Relay 18 will not energize since its left-hand winding extends to ground through the high resistance left-hand winding of relay 112. Relay 19 does not become energized since its right-hand winding is shunted by the low resistance right-hand winding of relay 112.

The operation of this system continues as above set forth. In the present case when sequence switch 45 reaches position 6, it remains in this position since neither of the paths for advancing it controlled by relays 18 and 19, have been completed. After the connection has been completed it may be released by the calling subscriber as previously described. In this case when sequence switch 58 passes through positions 14 and 15 an increased potential is supplied to the sleeve conductor to operate the message register from a source of potential 93, contact of sequence switch spring 86, conductor 120, brush 16 and its associated contact, conductor 121, winding of cut-off relay 111, and message register magnet 113, in paral-

parallel to ground. From this point the operation of the system is identical with that previously described.

From the foregoing it is obvious that the position assumed by the sender sequence switch is the controlling factor which determines whether or not a charging current is to be supplied to the calling line, and in case charging current is required it also determines the character of current to be supplied. It is also obvious that the relays 18 and 19 control the selection of the sequence switch charging position, and that these relays are in turn dependent upon electrical characteristics of the calling line tests.

In order to bring out more clearly the operativeness of the systems, the following characteristics are suggested in connection with relays 18 and 19. Relay 19 will operate on direct ground but will not operate on ground through a high resistance, such as the left-hand winding of relay 112. Neither will relay 19 operate when shunted by the low resistance such as the right-hand winding of relay 112. Relay 18 will operate on direct ground but will not operate when shunted by a low resistance such as the winding of line relay 2. Neither will it operate in series with a high resistance such as the left-hand winding of relay 112.

What is claimed is:

1. In a telephone exchange system, calling subscribers' lines equipped for various classes of service, called subscribers' lines, an automatic switch for interconnecting calling and called subscribers' lines, a registering device, means to operate said registering device to record the class of service to which the calling line is entitled, charging means, and automatic means to govern the operation of said charging means in accordance with the setting of said registering device.

2. In a telephone exchange system, calling and called subscribers' lines, an automatic switch for interconnecting said lines, certain ones of said calling lines being equipped with coin collect devices, others of said calling lines being equipped with message registers, and others of said calling lines being flat rate lines, means for extending a calling line to said automatic switch, charging means, and discriminating means automatically controlled in accordance with the class of service to which the calling line is entitled, to govern the operation of said charging means.

3. In a telephone exchange system, calling subscribers' lines equipped for various classes of service, called subscribers' lines, an automatic switch for interconnecting said calling and called subscribers' lines, means for extending a calling line to said automatic switch, a registering device, means to

operate said registering device to record the class of service to which the calling line is entitled, charging means, and automatic means to govern the operation of said charging means in accordance with the setting of said registering means. 70

4. In a telephone exchange system, calling subscribers' lines equipped for various classes of service, called subscribers' lines, an automatic switch for interconnecting calling and called subscribers' lines, means governed by a calling subscriber to control the operation of said automatic switch, a registering device, means to operate said registering device to record the class of service to which the calling line is entitled, charging means, and automatic means to govern the operation of said charging means in accordance with the setting of said registering means. 75 80 85

5. In a telephone exchange system, calling and called subscribers' lines, an automatic switch for interconnecting said lines, certain ones of said calling lines being equipped with coin collect devices, others of said calling lines being equipped with message registers, and others of said calling lines being flat rate lines, automatic means for extending a calling line to said automatic switch, charging means, and discriminating means automatically controlled in accordance with the class of service to which the calling line is entitled, to govern the operation of said charging means. 90 95

6. In a telephone exchange system, calling subscribers' lines, equipped for various classes of service, called subscribers' lines an automatic switch for interconnecting calling and called subscribers' lines, an automatic switch for extending connection from a calling line to said automatic switch, a registering device, means to operate said registering device to record the class of service to which the calling line is entitled, charging means, and automatic means to govern the operation of said charging means in accordance with the setting of said registering device. 100 105 110

7. In a telephone exchange system, calling and called subscribers' lines, an automatic switch for interconnecting said lines, certain ones of said lines being equipped with coin collect devices, other of said calling lines being equipped with message registers, and others of said calling lines being direct lines, a distributing switch for extending a calling line to said automatic switch, a contact bank for said distributing switch in which said calling lines terminate, means to supply characteristic potentials to said terminals in accordance with the class of service to which a calling line is entitled, a group of relays, variably operative charging means, and means to energize said relays in various combinations to control the operation of said charging means. 115 120 125 130

8. In a telephone exchange system, calling and called subscribers' lines, means for interconnecting said lines, said calling lines being equipped for various classes of service, means to supply said calling lines with characteristic electrical potentials in accordance with the class of service to which said lines are entitled, and a discriminating de-

vice selectively responsive to said potentials to govern the charging of calls to said calling lines. 10

In witness whereof I hereunto subscribe my name this 17th day of December A. D. 1920.

ALBEN E. LUNDELL.
